UNITED STATES PATENT OFFICE.

EDWARD G. SONNEMANN, OF ST. LOUIS, MISSOURI.

WINDOW-OPERATING MECHANISM FOR VEHICLE DOORS.

1,412,142.

Specification of Letters Patent. Patented Apr. 11, 1922.

Application filed April 11, 1921. Serial No. 460,401.

To all whom it may concern:

Be it known that I, EDWARD G. SONNEMANN, a citizen of the United States, residing at St. Louis, Missouri, have invented a certain new and useful Improvement in Window-Operating Mechanism for Vehicle Doors, of which the following is a full, clear, and exact description, such as will enable others skilled in the art to which it appertains to make and use the same.

This invention relates to devices of the character that are used on automobiles and other vehicles equipped with closed bodies for raising and lowering the windows that are slidingly mounted in the doors of the body.

The main object of my invention is to provide a window operating mechanism for vehicle doors that is inexpensive to manufacture and install, easy to operate and of such design that it is not liable to get out of order when in use.

Figure 1 is a vertical sectional view of a vehicle door equipped with a window operating mechanism constructed in accordance with my invention.

Figure 2 is a front elevational view of my improved window operating mechanism.

Figure 3 is a detail view, showing the cam on the operating shaft in the position it occupies when the window of the door is closed.

Figure 4 is a detail view, showing how said cam raises the window sufficiently to disengage the two co-operating interlocking portions on the window sash and on the door.

Figure 5 is a detail view, showing how said cam draws the window sash inwardly with relation to the door sufficiently to permit the sash to move downwardly into the pocket in the door.

Figure 6 is a detail view, illustrating the cam on the operating shaft in the position it occupies just before said cam passes out of engagement with the part on the window sash with which said cam co-operates; and

Figure 7 is a top plan view of the cam on the operating shaft.

Referring to the drawings which illustrate the preferred form of my invention, A designates a vehicle door of the kind used on closed vehicle bodies; B designates a window sash slidingly mounted in said door and adapted to be lowered into a pocket in the door when it is desired to open the

window, C designates a substantially hook-shaped device arranged transversely of the window sash at the lower edge of same, and D designates a vertically-disposed flange 60 that extends transversely of the door at the upper edge of the sash pocket and which co-operates with the hook-shaped device C on the sash to sustain the sash in its elevated position when the window is closed. The 65 parts A, B, C and D are of conventional construction and may be formed in various ways without departing from the spirit of my invention.

My invention consists of a mechanism of 70 novel construction for raising and lowering the sash B and for moving the hook-shaped device C on said sash into and out of engagement with the part D on the door with which said device C co-operates to sustain 75 the sash in its elevated position. Said mechanism preferably comprises a vertically disposed operating shaft 1 having its upper and lower ends journaled in suitable bearings 2 on the door, only the upper bearing being shown, a worm 3 on said shaft, a nut 4 co-operating with said worm and operatively connected with the window sash B, means for rotating the shaft 1 in opposite directions, such, for example, as a bevelled gear 5 mounted on the door, and a bevelled gear 6 on the operating shaft that meshes with the gear 5, the gear 5 being equipped with a handle or other suitable device 7 by which said gear may be rotated, 90 and means separate and distinct from said worm and nut 3 and 4, respectively, for moving the sash B relatively to the door A in such a manner as to engage and disengage the co-operating interlocking portions C and 95 D on the sash and door.

In the form of my invention herein illustrated the means just referred to consists of a cam E rigidly connected to the operating shaft 1 preferably at a point slightly below 100 the gear 6 on said shaft, and an inwardly-projecting arm F at the lower edge of the window sash that co-operates with the cam E. The cam E is provided with an inclined top face α that co-operates with the inwardly-projecting arm F on the window sash and which is of such form that it will raise and lower the sash slightly during a complete revolution of said cam, and said cam E is also provided with a substantially 105 eccentric groove γ that receives a depending projection β on the inner end of the

- arm F, as shown more clearly in Figures 3 to 7, inclusive, the function of said groove and projection y and z, respectively, being to move the sash B inwardly and outwardly 5 with relation to the door, so as to shift the hook-shaped device C on the sash into and out of the vertical plane in which the co-operating device D on the door lies. The nut 4 previously referred to through which 10 the worm 3 on the operating shaft passes is provided with a horizontally-disposed shank or projection 4^a, as shown in Figure 1, that projects outwardly, and the window sash B is provided at its lower end with a depend- 15 ing plate 8 having a vertically-disposed, elongated slot 8^a therein for receiving the horizontally-disposed shank or projection 4^a on the nut 4, thus providing a connection between the window sash and the nut 4 20 which permits the sash to move longitudinally slightly with relation to the nut 4 when the sash is being moved by the cam E on the operating shaft, as hereinafter described.
- 25 When the sash is in its closed position with the hook-shaped device C thereon in interlocking engagement with the transversely-disposed flange D on the door, the parts of my improved sash operating mech- 30 anism occupy the position shown in Figures 1 and 3, the depending projection z of the inwardly-projecting arm F on the sash being positioned at one end of the eccentric groove y in the cam E. When it is desired 35 to lower the sash B into the pocket in the door A the handle or operating device 7 of the gear 5 is turned in a direction to move the cam E into the position shown in Figure 4, the inclined or spiral top surface x 40 of said cam causing the sash to move upwardly with relation to the door sufficiently to disengage the device C on the sash from the co-operating part D on the door. As the rotary movement of the operating shaft 45 1 is continued the eccentric groove y in the cam E causes the lower edge portion of the sash B to move inwardly relatively to the door sufficiently to carry the hook-shaped device C on the sash out of the vertical 50 plane of the co-operating part D on the door, as shown in Figure 5. Further rotary movement of the operating shaft 1 in this same direction causes the sash B to move downwardly into the position shown in Figure 6, due, of course, to the shape of the inclined top face x of the cam E. When the cam reaches this position the depending projection z on the arm F is positioned at the opposite end of the eccentric groove y 55 in said cam, and consequently, the further rotary movement of the operating shaft in the same direction causes the arm F to pass out of engagement with the cam E, and thus bring the nut 4 into service. In other words, 60 during the first portion of the operation of 65 lowering the sash the movement of the sash with relation to the door is effected by the cam E on the operating shaft and the arm F on the sash, but after said arm has passed out of engagement with said cam, the weight 70 of the sash will be sustained by the laterally-projecting shank 4^a on the nut 4, and consequently, the sash will be moved downwardly into the pocket in the door by the movement imparted to said sash by the nut 4. 75
- To raise the sash the operating handle 7 on the gear 5 is rotated in the opposite direction, so as to cause the nut 4 to travel upwardly on the worm 3 on the operating shaft, and when the sash reaches a certain 80 height the depending projection z of the arm F on the sash enters one end of the eccentric groove y in the cam E. Thereafter, the rotary movement of said cam causes the sash to be raised to such a position that the hook-shaped device C on the sash is higher than the co-operating part D on the door, to be thereafter moved outwardly so as to bring the device C into the vertical plane of the device D on the door 85 and to thereafter be moved downwardly so as to bring the device C into interlocking engagement with the part D on the door.
- A window sash operating mechanism for vehicle doors of the construction above described is inexpensive to manufacture and install, and as it is composed of only a few rugged parts of simple design, it is not liable to get out of order when in use. 90
- Having thus described my invention, what I claim as new and desire to secure by Letters Patent, is:
1. A window sash operating mechanism for vehicle doors, comprising a nut and worm for raising and lowering the sash, an operating device for actuating one of said elements, and a separate means actuated by said operating device, for positively moving the sash relatively to the door so as to engage and disengage the co-operating parts on the sash and door that sustain the sash in its raised position. 105
  2. A window sash operating mechanism for vehicle doors of the type in which the sash and door are equipped with co-operating interlocking parts that are in engagement with each other when the window is closed, consisting of an operating shaft journaled in the door, one means actuated positively by said shaft for moving the sash in two different directions so as to disengage and engage the co-operating interlocking parts on the sash and door, and an independent means operated by said shaft for raising and lowering the sash relatively to the door. 110
  3. A window sash operating mechanism for vehicle doors, comprising an operating shaft journaled in the door, means actuated by said shaft for positively lowering the sash 115

sash into the pocket in the door and for raising the sash out of said pocket, and an independent means directly connected with said shaft for moving the lower edge 5 portion of the sash in two directions at an angle to each other, for the purpose described.

4. A vehicle door provided with a window sash that is adapted to be lowered into a 10 pocket in the door, a substantially hook-shaped part on said sash that extends over a co-operating part on the door and sustains the sash in its raised position, an operating shaft journaled in the door, a device 15 directly connected to said shaft and a co-operating part on the sash for moving the sash vertically and horizontally as to disengage the hook-shaped device thereon from the co-operating part on the door during 20 the operation of lowering the sash, and an independent means actuated by said shaft for lowering the sash into the pocket of the door.

5. A window sash operating mechanism 25 for vehicle doors, comprising an operating shaft journaled in the door and provided with a worm, a nut that co-operates with said worm to raise and lower the sash, a cam on said operating shaft, and a part 30 on the sash that co-operates with said cam to effect the final seating of the sash during the operation of closing the window and to effect the preliminary movement of the sash during the operation of opening the window.

35 6. A window sash operating mechanism for vehicle doors of the kind in which the sash is provided with a substantially hook-shaped part that laps over a co-operating part on the door when the window is closed, 40 comprising an operating shaft carried by the door, a cam on said shaft, a part on the sash that co-operates with said cam to move the sash upwardly and downwardly slightly with relation to the door so as to disengage 45 and engage the co-operating interlocking parts on the sash and door, and means on said cam for moving the sash transversely with relation to the door so as to shift the hook-shaped part on the sash out of the vertical plane of the co-operating part on the door.

50 7. A window sash operating mechanism for vehicle doors, comprising an operating shaft carried by the door and provided with a worm, a nut co-operating with said worm and operatively connected with the sash, a cam on said operating shaft provided with an eccentric groove, a laterally-projecting part on the sash that bears against said cam

when the sash is in a certain zone, and a 60 projection on said part that is adapted to ride in the eccentric groove in said cam, for the purpose described.

8. A window sash operating mechanism 65 for vehicle doors, comprising an operating shaft journaled in the door and provided with a worm, a nut through which said worm passes, means for connecting the sash with said nut in such a manner that the sash is capable of moving slightly longitudinally with relation to the nut, an arm 70 connected to said sash, and a cam on the operating shaft co-operating with said arm and having a face of such form that it will raise and lower the sash slightly with relation to the door during one complete revolution of the cam.

9. A window sash operating mechanism 75 for vehicle doors, comprising an operating shaft journaled in the door and provided 80 with a worm, a nut through which said worm passes, means for connecting the sash with said nut in such a manner that the sash is capable of moving slightly longitudinally with relation to the nut, an arm 85 connected to said sash, a cam on the operating shaft co-operating with said arm and having a face of such form that it will raise and lower the sash slightly with relation to the door during one complete revolution of 90 the cam, an eccentric groove in the operative face of said cam, and a projection on said arm that travels in said groove.

10. A vehicle door provided with a sliding window sash that is adapted to be 95 lowered into a pocket in the door, a substantially hook-shaped part arranged transversely of the sash adjacent the lower end of same, a transversely-disposed part on the door over which said hook-shaped part overlaps when the sash is in its closed position, an operating shaft journaled in the door and provided with a worm, a nut mounted on said worm and provided with a horizontally-disposed shank, a member on the sash provided with an elongated slot for receiving said shank, a cam on said operating shaft provided with a substantially spiral operating face equipped with an eccentric groove having both of its ends open, and an arm 100 105 projecting inwardly from the lower edge portion of the sash and provided with a depending projection that is adapted to enter said groove and thus move the lower edge portion of the sash transversely with relation to the door, for the purpose described.

EDWARD G. SONNEMANN.
